LOOSE-LEAF BINDER

Clifford Brooks Stevens, Milwaukee, Wis., assignor to The Heinr Company, Milwaukee, Wis., a corporation of Wisconsin

Application October 11, 1943, Serial No. 505,717

8 Claims. (Cl. 129—10)

1

This invention relates to a loose leaf binder for catalogues, note books and the like.

With the scarcity of metal during the war, many attempts have been made to construct ring binders from plastic compositions. The chief difficulties have arisen from attempting to follow the designs of metal binders without change and the inability of adapting plastics to the more intricate operating and locking mechanisms.

The principal object of the present invention is to provide a simple and more efficient binder particularly adapted for construction by plastic molding.

Another object is to provide a binder in which papers on one side are held in substantial alignment vertically, while those on the other side are held in the relation usually resulting from the arcuate ring binder posts.

Another object is to provide a plastic binder which is rigid and which employs two longitudinally pivotal base elements interlocked in such a manner that the posts of the binders are always tightly engaged without danger of spreading when the binder is closed.

Another object is to provide a plastic binder in which the posts are protected against undue stress.

Another object is to provide a plastic binder with a strong and durable lock without requiring the use of intricate metal parts.

Another object is to provide a binder that is lighter in weight and more serviceable than the metal binders heretofore employed.

Another object is to provide a binder that can be made of plastic material of different colors to suit the needs of various industries and users.

The several features of the invention are illustrated in the embodiment shown in the accompanying drawings.

In the drawings:

Figure 1 is a top plan view of the binder when closed and locked;

Fig. 2 is a similar view of the binder in unlocked and open position;

Fig. 3 is an enlarged lower end elevation of the binder in closed position;

Fig. 4 is a side elevation of the binder in closed position;

Fig. 5 is an enlarged transverse section through the hinge taken on line 5—5 of Fig. 1;

Fig. 6 is an enlarged transverse section through the binder at the location of a securing rivet taken on line 6—6 of Fig. 1;

Fig. 7 is an enlarged central transverse section

2

showing the tongue and groove interlock taken on line 1—1 of Fig. 1; and

Fig. 8 is an enlarged top plan view of the locking end of the binder with parts broken away.

5 The binder illustrated is a combination post and ring binder in which the posts 1 for holding the paper on the right-hand side of the book are upright and vertical with a substantially right angle turn 2 at the top, while the corresponding posts 3 on the left-hand side are of curved arcuate or ring shape with only a short upright section at the base of the posts.

The posts 1 are cast integrally with a movable base strip 4 which has a substantial thickness to 15 lend rigidity thereto. The strip 4 is nearly one-half the width of the binder and has a projecting hinge 5 at one end.

The posts 3 are cast integrally with a stationary base strip 6 of the same thickness as strip 4 and which is secured by rivets 7 disposed along its length to the back of the catalogue cover 8 to secure the binder in place. The rivets 7 are disposed near to the center line of the base in order to hold the binder from displacement with 25 in its cover.

The bottom end of the strip 6 has its lower half recessed to receive the hinge 5 of the movable strip 4 and a rivet pin 9 pivotally secures the two together to allow the movable strip 4 to pivot longitudinally from a closed position parallel to strip 6 and in which the upper ends of posts 1 engage the upper ends of posts 3 to an open position at nearly right angles to strip 6 where the posts are separated for the insertion and removal 35 of properly punched loose leaves.

The binder is locked in closed position at the end opposite to hinge 5 by means of a locking slide 10 which is of approximately one-half the thickness of strips 4 and 6, the latter being recessed beneath their ends to receive the slide.

The slide 10 has an upright cross member 11 at its outer end which serves for manual operation of the slide longitudinally of the binder. The slide 10 is riveted to the overlying end portion 12 of strip 6 by a loose rivet 13 passing through a longitudinal slot 14 in the slide.

The longitudinal position of slide 10 is determined by a fixed detent 15 projecting laterally from an upright side member 16 of the slide and entering alternate recesses 17 and 18 in the side of the end member 12 of strip 6. The side surface of member 12 between recesses 17 and 18 is curved outwardly to provide for a snap action of the detent 15 in passing from one recess to the other and to insure ease of operation of the slide

and securing the same in its opposite positions of movement. The flexibility of the plastic material from which the parts are made, coupled with the tolerances in the fit of the parts, enables the detent to ride over the curved surface between recesses 17 and 18 when the slide 10 is manually forced outwardly or inwardly.

The strip 4 is locked in closed position by slide 10 by means of a lug 19 on the slide adjacent end member 11 and fitting into a recess 20 in the outer corner of the overlying end portion 21 of strip 4. The length of lug 19 longitudinally of the slide 10 should be no greater than the longitudinal movement of the slide so that when the slide is pulled outwardly the end of member 21 on strip 4 will freely pass the lug 19 in swinging strip 4 laterally to open position.

The strips 4 and 6 are interlocked vertically for substantially their full length when in closed position to give rigidity to the base of the binder and reenforce the movable strip 4 against bending and consequent release of some of the post connections. This vertical interlock of strips 4 and 6 is provided by a tongue and groove, the tongue 22 being preferably disposed centrally in the edge of strip 4 and the matching groove 23 being preferably disposed in the corresponding meeting edge of strip 6. The tongue 22 and groove 23 extend substantially for the full length of the body of the strips except for interruptions 24 necessitated by the securing rivets 7. The depth of the tongue and groove should be for a substantial portion of the width of the binder base and will be limited by the molding restrictions for the particular plastic employed. The binder base composed of strips 4 and 6, as illustrated, has a width of about one inch and a thickness of about three-sixteenths of an inch. The tongue 22 has a thickness a little less than one-sixteenth inch and is centered vertically with respect to strip 4. The groove 23 is designed to fit the tongue with reasonable closeness without interfering with the closing of the binder.

The posts 1 and 3 have fillets 25 at their lower ends where they merge in the base strips to strengthen the posts. The upper ends of corresponding posts are interlocked when closed together. This interlock preferably comprises a recess 26 in the end of each post 1 and a central curved projection 27 at the end of each corresponding post 3. The projection 27 is designed relative to recess 26 to provide for seating only at the outer rim where the abutting shoulders 28 of the respective posts come together. This insures that there will be no square corner ledge exposed for catching the paper as it is turned in either direction from one side of the binder to the other. If desired, the under side of the meeting shoulders 28 of the posts may be filed off on a slight upward taper to insure that there will be no ragged edge to catch the paper.

The binder is designed to provide that the respective posts 1 and 3 come together at the top before the strips 4 and 6 come into final locking position in closing. This places the structure under a pre-stressed condition tending to hold the posts closed at all times.

The binder is preferably constructed of a relatively hard plastic to have the required rigidity. Softer and more flexible plastics are not suitable. The plastics may be of any suitable color or mixture of colors desired, thereby providing attractiveness to the binders unattainable with the former metal binders. The lightness of weight is an added feature of importance, it being possible

to provide a binder embodying the invention and weighing about two-and-a-half ounces as compared to a corresponding metal binder that weighed nearly double for the same size catalogue.

The ease with which a binder of the construction described can be molded from plastic materials and the accuracy obtainable makes the manufacture of the binder less costly and more simple and adaptable for mass production methods.

The actual number of posts in the length of the binder may be varied to suit the need. The molds may be constructed to provide the maximum number of posts required, and by blocking off mold cavities the posts may be reduced to three, if it is desired to produce a three ring binder.

The posts do not extend laterally beyond the sides of the base. This feature is of considerable importance where plastic compositions employed are either weak or brittle since there is no danger of the posts being broken by shock or excessive stress when the binder is dropped, or of being crushed in shipment, as would be the case if the posts extended beyond the sides of the base as in most steel binders.

By providing upright posts 1 on the right-hand side of the binder, the sheets on the normal working side of a notebook are all held in vertical alignment, most suitable for support in writing. Furthermore, the relatively short top hook on the vertical posts facilitates the insertion and removal of sheets from this side, the sheets almost dropping vertically onto the posts.

Various features of the invention might be employed in metal binders, and various embodiments of the invention may be employed within the scope of the accompanying claims.

I claim:

40. 1. In a loose leaf binder of the class described, a base of uniform thickness and width throughout comprising two longitudinal strips disposed edge to edge, a pivotal connection at one end for securing said strips together and providing for lateral separation of the same at the opposite end, a slide of a width substantially the same as the strips at the laterally separable end of said strips for laterally locking the same in closed position with the strips being recessed beneath their ends to receive the slide, said slide underlying the recessed end of the strips to maintain the uniform base dimensions and protect the lock against injury.

45. 2. In a loose leaf binder of the class described, a base of uniform thickness and width throughout comprising two longitudinal strips disposed edge to edge, a pivotal connection at one end for securing said strips together and providing for lateral separation of the same at the opposite end, a slide of a width substantially the same as the strips at the laterally separable end of said strips for laterally locking the same in closed position with the strips being recessed beneath their ends to receive the slide, said slide underlying the recessed end of the strips to maintain the uniform base dimensions and having a slot therein to receive a loose rivet member to secure the slide to one of the strips for limited endwise movement relative to the strips.

50. 3. A loose leaf binder of the class described comprising two longitudinal strips of different width and interlocked together longitudinally edge to edge, a pivotal connection at one end thereof for securing said strips together and 55 mounting the same for lateral separation, manu-

ally operable means for locking said strips against lateral separation, a plurality of substantially straight posts extending vertically from the narrow strip, and a plurality of curved posts extending vertically from the wider strip complementary to the vertical posts of the narrower strip and into interlocking engagement therewith, the width of the strips determining the location of the curved posts on the wider strip and the location of the straight posts on the narrower strip to provide a balanced binder with the longitudinal interlock of the posts located in substantially the same vertical plane as the longitudinal interlocking line of the strips.

4. A lightweight durable loose leaf ring binder of molded set plastic material secured to the back of a binder cover and comprising, a thick base member of substantially uniform width and thickness and constituted of a pair of strips disposed edge to edge with the adjacent edges thereof vertically interlocked for substantially the full length thereof, means mounting said strips for relative lateral separation, and a set of binder posts molded integrally with and extending vertically upward from each of said strips adjacent the respective outer edge thereof, the posts of each set curving inwardly to meet and engage the corresponding posts of the other at a parting line substantially within the vertical plane of the meeting edges of the strips, and said posts being disposed substantially entirely between the vertical planes of the opposite side edges of the base to protect the same against breakage.

5. A lightweight durable loose leaf ring binder of molded set plastic material secured to the back of a binder cover and comprising, a thick base member of substantially uniform width and thickness and constituted of a pair of laterally separable strips disposed edge to edge with the adjacent edges thereof vertically interlocked for substantially the full length thereof, a pivotal connection between said strips at one end thereof providing such lateral separation therefor, a lock for securing said strips in closed relation at the end thereof opposite said pivotal connection, said pivotal connection and lock being disposed substantially within the width and thickness of the base to protect the same from breakage, and a set of binder posts molded integrally with and extending vertically upward from each of said strips adjacent the respective outer edge thereof, the posts of each set curving inwardly to meet and engage the corresponding posts of the other at a parting line substantially within the vertical plane of the meeting edges of the strips, and said posts being disposed substantially entirely between the vertical planes of the opposite side edges of the base to protect the same against breakage.

6. A lightweight durable loose leaf ring binder of molded set plastic material secured to the back of a binder cover and comprising, a thick base member of substantially uniform width and thickness and constituted of a pair of laterally separable strips of different width disposed edge to edge with their adjacent edges interlocked by a tongue and groove connection throughout substantially the full length thereof, means providing for the lateral separation of the narrower strip from the wider of said strips, rivets passing through the wider of said strips and securing the same to the back of the binder cover along a longitudinal line substantially central of the base, and a set of binder posts molded integrally with and extending vertically upward from each of said strips adjacent the respective outer edge

thereof, the posts of each set curving inwardly to meet and engage the corresponding posts of the other at a parting line substantially within the vertical plane of the meeting edges of the strips, and said posts being disposed substantially entirely between the vertical planes of the opposite side edges of the base to protect the same against breakage.

7. A lightweight durable loose leaf ring binder of molded set plastic material secured to the back of a binder cover and comprising, a thick base member of substantially uniform width and thickness and constituted of a pair of laterally separable strips of different width disposed edge to edge with their adjacent edges interlocked by a tongue and groove connection throughout substantially the full length thereof, means providing for the lateral separation of the narrower strip from the wider of said strips, rivets passing through the wider of said strips and securing the same to the back of the binder cover along a longitudinal line substantially central of the base, a pivotal connection between said strips at one end thereof, a lock for securing said strips in closed relation at the end thereof opposite said pivotal connection, said pivotal connection and lock being disposed substantially within the width and thickness of the base to protect the same from breakage, and a set of binder posts molded integrally with and extending vertically upward from each of said strips adjacent the respective outer edge thereof, the posts of each set curving inwardly to meet and engage the corresponding posts of the other at a parting line substantially within the vertical plane of the meeting edges of the strips, and said posts being disposed substantially entirely between the vertical planes of the opposite side edges of the base to protect the same against breakage.

8. A lightweight durable loose leaf ring binder of molded set plastic material adapted to be secured to the back of a binder cover, comprising a thick base member of substantially uniform thickness and width and constituted of a pair of laterally separable strips of the full thickness of the base disposed edge to edge and having integrally molded therewith a set of ring posts rising substantially vertically from each strip in the thick body portion thereof near the outer edge, means providing for the lateral separation of said strips, and means for interlocking and securing said strips in edge to edge relation with the corresponding posts of each set in engagement at their upper ends to constitute a set of closed rings for the binder, said interlocking means including a vertical interlock for the adjacent edges of said strips for substantially the full length thereof, and said posts being interlocked under pressure when said strips are closed together in locked position.
